UNITED STATES PATENT OFFICE.

HARRY E. BELL, OF FORT WORTH, TEXAS.

TOY RUBBER SHOOTER.

Application filed April 26, 1926. Serial No. 104,620.

My invention relates to toys and more particularly to imitation pistols for shooting rubber bands and the like; and the object is to provide simple devices which can be produced and sold at small cost for amusement purposes and which are harmless. Other objects and advantages will be fully explained in the following description and the invention will be more particularly 10 pointed out in the claims.

Reference is had to the accompanying drawing which forms a part of this application.

Fig. 1 is a side elevation of the toy.

15 Fig. 2 is a rear elevation of the same.

Fig. 3 is a side elevation of a toy, showing a variation in the spring.

Fig. 4 is a side elevation, illustrating a variation in the release device.

20 Similar characters of reference are used to indicate the same parts throughout the several views.

This device includes a body having a member 1 corresponding to the barrel of 25 the gun or pistol and a handle 2 corresponding to the handle of a pistol. Near the juncture of the handle with the barrel a recess 3 is made in the handle. A trigger 4 is pivotally mounted on the handle by 30 means of a stirrup 5 which has the terminals driven into the handle 2 and the loop of the stirrup rests in a notch or recess 6 in the handle 2. The trigger 4 has a lug 7 which is adapted to press the charge or 35 load in the recess 3. A coiled spring 8 has one end 9 caught in a recess 10 in the outer face of the trigger 4 and the other end 11 bearing against the handle 2. The spring 8 keeps the trigger 4 pressed towards the 40 recess 3 so that the lug 7 will press a portion of the charge or load material into the recess 3. The material used by this toy is elastic bands 12. At the outer end of the toy, a band 12 is caught on the end of the 45 barrel and stretched back over the juncture of the handle with the barrel and placed in the recess 3. The trigger 4 is raised out of the recess by pressing on the end 13 so that the rubber band may be inserted in the 50 recess 3. The rubber or elastic band is folded upon itself and the lug 7 presses on the folded end or near the end.

After the device is loaded, the load will be discharged when the lug 7 is raised from 55 the end of the load. This is done by press-

ing on the end 13 of the handle. In loading the device, the elastic band 12 is caught across the end of the barrel, as shown in Fig. 1, and then stretched back on top of the barrel and then downwardly on the rear 60 part of the barrel or the juncture of the barrel with the handle and pressed into the recess 3.

The variation shown in Fig. 3 consists in using a spiral spring 14 which is used instead of the spring 8; and placing the spring 14 at a different location.

Instead of pressing on the trigger end 13, an additional trigger 15 may be pivotally mounted on the handle, as shown in Fig. 4, 70 and a stirrup 16 used to pull on the trigger end 13 when the trigger 15 is actuated.

In addition to the objects above set forth, the toy may be used as an advertising medium, as the device can be manufactured 75 and given along with some other salable article, and there being ample space for printing or stamping advertising matter on the sides of the barrel and handle.

What I claim is,—

1. A rubber shooter comprising a body provided with a barrel and a handle therefor having a recess near the juncture of the handle with said barrel; and a spring-actuated trigger pivotally mounted on said 85 body and provided with a lug adapted to press in said recess.

2. A rubber shooter comprising a body provided with a barrel and a handle therefor having a recess near the juncture of the handle with said barrel, a trigger in the form of a lever fulcrumed on said handle and provided with a lug adapted to press into said recess for holding a charge, and a spring engaging said handle and said lever 95 and adapted to press said lug into said recess for holding a charge.

3. A toy rubber shooter comprising a body provided with a barrel a handle therefor having a recess near the juncture of the handle with said barrel, a trigger lever provided with a lug adapted to press into said recess, a stirrup engaging said body and said lever and forming a fulcrum for said lever, and a spring normally pressing into 105 said recess.

In testimony whereof, I set my hand, this 21st day of April, 1926.

HARRY E. BELL.
